UNITED STATES PATENT OFFICE.

CHARLES S. ROGERS, OF HOT SPRINGS, ARKANSAS.

DESIGN FOR A BADGE.

SPECIFICATION forming part of Design No. 33,449, dated October 30, 1900.

Application filed September 5, 1900. Serial No. 29,094. Term of patent 34 years.

To all whom it may concern:

Be it known that I, CHARLES S. ROGERS, a citizen of the United States, residing at Hot Springs, in the county of Garland and State of Arkansas, have invented and produced a new and original Design for a Badge; and I do hereby declare the following to be a full, clear, and exact description of the same, reference being had to the accompanying drawings, forming a part thereof.

Figure 1 is a plan view of a badge, showing my design. Fig. 2 is a sectional view taken on the line X X of Fig. 1.

As shown in the drawings, the leading or material feature of my design consists of a crescent, the horns of which are pointed down. In the rear of this crescent are crossed two daggers, the handles of which extend a

little above the crescent, while the points extend downwardly almost to near the ends of the horns. Between the two horns of the crescent is the representation of a double-headed eagle holding in each claw an arrow, which are crossed and the ends pointing downwardly.

Having described my invention, what I claim as new, and desire to secure by Letters Patent, is—

The design for a badge, as herein shown and described.

In testimony whereof I affix my signature in presence of two witnesses.

CHARLES S. ROGERS.

Witnesses:

W. P. WALSH,
W. M. ROGERS.
